(57) **CLAIM**

The ornamental design for an electrical bus bar support, as shown and described.

DESCRIPTION

FIG. 1 is a front and bottom perspective view of an electrical busbar support showing our new design;

FIG. 2 is a front and top perspective view thereof;

FIG. 3 is a top plan view thereof;

FIG. 4 is a bottom plan view thereof;

FIG. 5 is a front elevation view thereof;

FIG. 6 is a side elevation view thereof;

FIG. 7 is an opposite side elevation view thereof;

FIG. 8 is a front and top perspective view thereof, in use condition; and,

FIG. 9 is another front and top perspective view thereof, in use condition.

A rear elevation of the electrical bus bar support constitutes no part of the claimed design. In the drawings, the broken lines depict unclaimed subject matter only and form no part of the claimed design.
